H. G. HUGHES

AUTOMOBILE LOCK

Filed Aug. 11, 1926

FIG. 1.

FIG. 4.

FIG. 6.

FIG. 7.

Inventor

Henry G. Hughes

By

R. M. Thomas
Attorney

UNITED STATES PATENT OFFICE.

HENRY G. HUGHES, OF MENDON, UTAH.

AUTOMOBILE LOCK.

Application filed August 11, 1926. Serial No. 128,682.

My invention relates to locks for automobiles and has for its object to provide a new and efficient lock for an automobile which will be safer than the ordinary key lock and which will be operated by the driver of the car as a combination lock.

A further object is to provide a combination lock for automobiles which will lock both the lights and the ignition switches.

10 A still further object is to provide an economically constructed combination lock for the ignition and light switches for an automobile which will have less parts in its construction and which will not get out of order.

15 These objects I accomplish with the device illustrated in the accompanying drawings in which similar numerals and letters of reference indicate like parts throughout the several views and as described in the specification forming a part of this application and as pointed out in the appended claims.

20 In the drawings of which I have shown the best and most preferred manner of building my invention, Figure 1 is a front view of my lock. Figure 2 is a top view of the same. Figure 3 is a front view of the front plate used in my lock. Figure 4 is a front view 25 of the insulation plate used on the rear of my lock. Figure 5 is an edge view of the dial. Figure 6 is a front view of the dial. Figure 7 is a plan view of the switch. Figure 8 is a section on line 8—8 of Figure 1. Figure 9 is a plan view of the locking plug. And Figure 10 is a section on line 10—10 of Figure 9.

25 In the drawings I have shown the casing in which my lock is mounted and operated as A. On the front and closed side of said casing I provide a plate B in which the dials D are mounted and through which plate B the lock sleeve S is passed. On the rear side of the said casing A I provide an insulation plate E which closes the open side of the casing A. Bolts 1 are passed through the holes 2, cut in all of the plates and the casing A to secure the entire device together. The said plate B has two spaced apart holes 3 and 4 cut therethrough and on the back side of said plate the holes are bored larger, as at 5, and in which holes the dial plates D are rotatably carried and operated. A check or indentation 6 is made in the plate B on the upper side of each hole to mark the combination position. The dial plates

D are made of flat circular sheets of metal with the back side D² of larger diameter than the front, and have a knurled turning knob D¹ provided on the front side thereof by which they may be turned. Letters 7 are printed on the face of the dials D and smaller marks or indentations 8 are made in the face of said dials dividing the space in between the letters into equal parts to make it look as though more combinations were possible. Holes 9 are bored centrally through said dial plates D and through which holes the switch posts 10 are carried and rotatably operated. A slot 11 is cut in the back and enlarged side D² of the dial plates D through which a guide or catch 12 on the sleeve S passes when the combination has been worked. A similar groove 13 is cut in the edge of a switch plate 14, which plate is secured to the said post 10, and another plate of insulating material 15 is secured to the said plate 14. A switch spring 16 is secured to a cross plate 17, which is in turn secured to the said insulation plate 15. Hand levers 25 are secured to the free ends of the post 10 by which the switches may be operated. Wire connections 18 are provided on the back side of the said plate E and are connected with contact points 19 secured to the front side of the plate E, as shown in Figure 8, and with which point the springs 16 are brought into contact when the switches are turned. Both of the dials D are alike except that the slots 11 may be cut at different places on the periphery of the said dial plates. A locking sleeve S is passed through the entire casing A and the plates B and C through holes 20 bored through the entire assembly, and each of the said holes 20 has grooves or notches 21 cut in its periphery through which notches 21 the guides 12 pass when the locking sleeve is being changed. The said locking sleeve S has two guides 12 secured therein and said guides are held in place by a spring 22 secured inside the said sleeve S by the pin 23. A spring 26 is provided on the said sleeve S to normally hold said sleeve in place in the hole 20. A plug 27 is secured to the free end of said sleeve S to normally hold said spring on said sleeve S.

The operation of my device is as follows:

When it is desired to lock the ignition and light switches of the automobile, the locking sleeve S is pulled outwardly and turned a quarter turn so that the guides 12 will fit

into the cross slots 21. The sleeve S is then pushed into place again and the combinations turned on the dials D until the slots 11 are not in alinement with the guides 12, or 5 the slots 13. The switches will then be locked. To unlock the switches the combination numbers on the dials D will be turned until the predetermined combination is in place and the slots 11 are again in alinement 10 with the guides 12 and the slots 13. The sleeve S may then be drawn out and turned a quarter turn and pushed back into the former position again. The switches will then be free to move as desired. The spring 15 on the sleeve S holds the said sleeve normally against the plate B, as shown in Figure 2, which figure also shows by dotted lines the sleeve S drawn out.

Having thus described my invention, I 20 desire to secure by Letters Patent and claim:—

1. In a lock for automobiles the combination of a casing having holes bored therein with slots at right angles to each other in 25 the peripheries of the holes; a plate secured in front of said casing, with holes and slots therein similar to the holes in said casing and in alinement therewith; an insulated cover over the rear of said casing having a 30 central hole bored therethrough in alignment with the central holes in the casing and plate and with slots at right angles to each other in the periphery of said hole; dials operable in the holes in said plate with 35 the rear side of each of greater diameter than the front side and having slots cut in

the enlarged rear side of said dials through which guide members are slidable when all of the slots are in alignment; turning knobs on each of said dials with holes bored centrally therethrough; a switch post operated through the holes in said knobs; a switch attached thereto; contact members secured through said insulated cover adapted to be brought into contact with said switches by 45 turning said posts; a locking sleeve operable through the central hole in said casing, plate and cover; and guide members carried in said sleeve, operable in the slots in the periphery of the holes in the casing, plate 50 and cover, adapted to hold the locking sleeve rigid in the lock.

2. In a combination lock for automobiles the combination of a casing; dials mounted through the front of said casing, having 55 the back side of larger diameter than the front face and with slots cut in the periphery thereof; letters on the faces of said dials; a locking sleeve operable through a continuous hole through said lock, adapted to be 60 drawn out, turned a quarter turn and pushed back into said lock to release or lock the switches of said lock; guide members in said locking sleeve adapted to be passed through the slots in the periphery of said dials when 65 the combination has been worked; and switches through said lock adapted to be turned when released by the said locking sleeve.

In testimony whereof I have affixed my 70 signature.

HENRY G. HUGHES.
